SHOE CLEAT ASSEMBLY

Chester W. Dowd, Dover, and Henry G. Mogensen, Shrewsbury, Mass.

Application February 5, 1948, Serial No. 6,434

2 Claims. (Cl. 36—59)

1

This invention relates to athletic shoe cleats, and more particularly to the anchoring means by which such cleats are secured against the sole of a shoe. One method frequently employed to mount a cleat on a shoe sole is to provide the shoe with screws or bolts extending through the sole and projecting down therefrom, the bolts having flat heads which are sunk flush with the inner surface of the shoe sole. The cleats each contain a nut or female screw-threaded element by which they are screwed on the outwardly projecting portions of the bolts. When the shoes are in use, the cleats are subjected to severe stresses some of which may have a torsional effect on the cleats. It is highly desirable to secure the cleats in such a manner that they will not work loose and come off since an exposed bolt end is a dangerous hazard. Hence, various expedients have been devised for the purpose of preventing undesired rotation of a cleat on its bolt and for preventing rotation of any of the elements of the assembly with respect to the sole of the shoe.

According to the present invention, a washer is provided which has prongs on its periphery adapted to penetrate into the shoe sole and ratchet teeth projecting in the opposite direction to engage the base of a cleat, the washer being secured to the bolt by swaging against the bolt in an extruded neck previously formed in the center of the washer.

For a more complete understanding of the invention, reference may be had to the following description thereof, and to the drawing, of which—

Figure 1 is a perspective view of a locking washer embodying the invention;

Figure 2 is a fragmentary, sectional view of a shoe sole with the cleat anchor assembly and a tool for securing the parts of the assembly together; and

Figure 3 is a similar sectional view showing the completed cleat anchor assembly and a cleat.

The locking washer illustrated on the drawing preferably consists of a disk 10 of steel or other suitable malleable metal, having a series of prongs 12 at its periphery projecting at right angles to the plane of the disk. The disk is also provided with a circular series of ratchet teeth 14, preferably struck up from the plane of the disk so that they project from the face of the disk opposite to the prongs 12. A central neck 16 is extruded from the disk so as to project from the same face of the disk as do the ratchet

2

teeth 14. The extruded neck 16 has an interior diameter substantially equal to the outer diameter of a screw or bolt 20 which is extended through the shoe sole 22, the screw having a flat head 24 which is driven flush with the inner surface of the sole 22 and which may be made with fins 25 on its head to lock it against rotation. When the screw is in its position, as illustrated in Figures 2 and 3, it projects below the bottom surface of the shoe sole, the projecting portion being screw-threaded. A locking washer 10 is placed on the projecting portion of the screw 20 with the prongs 12 toward the outer surface of the shoe sole 22. The neck 16 fits closely about the screw 20. A suitable tool 30 is then struck against the locking washer 10. The head of this tool preferably has a diameter approximately equal to that of the disk 10 and is provided with a central bore 32 adapted to receive the screw 20. The bore is slightly flared, as at 34, at the end of the tool so that the mouth of the bore can receive the rim or extremity of the neck 16. The end face of the tool 30 is also provided with an annular groove or channel 36, arranged to receive the ratchet teeth 14 so that these are not pressed when the tool engages the disk 10. When the tool is driven home, it pushes the disk 10 into face-to-face engagement with the bottom of the sole 22, crimps or swages the neck 16 against the screw 20 into binding engagement therewith so that the disk 10 is permanently secured to the screw, and causes the prongs 12 to penetrate into the sole, as shown in Figure 3. Thus, the screw and disk are rigidly joined together as a unit and the portion of the threaded shank of the screw which projects beyond the neck 16 is ready to receive an ordinary cleat 40 of rubber or an equivalent, with a nut 42 embedded therein.

One common form of cleat has a shallow recess 44 in its end face. The ratchet teeth 14 are preferably so arranged that the circle defined by the outer ends of the teeth is of slightly greater diameter than the recess 44. When the cleat is screwed on to the screw 20, the ratchet teeth engage both the bottom and side surfaces of the recess 44 to hold the cleat against reverse rotation which would loosen it.

The swaging operation by which the washer is secured to the shank of the screw 20 expedites the assembling process since the washer is quickly slipped over the screw shank, and one blow of the tool 30 fixes it in place, making a virtual unit with the screw 20. The fins 25 and

the prongs 12 cooperate to prevent any rotation of this unit with respect to the shoe sole.

We claim:

1. In combination with an athletic shoe sole, a screw extending out through said sole, and a lock washer permanently secured to said screw, said washer having prongs at its periphery penetrating into the bottom surface of said sole and ratchet teeth projecting from the bottom surface of the washer, said washer having a neck surrounding a portion of said screw, said neck being tightly swaged against said screw.

2. In combination with a shoe sole, a cleat assembly comprising a screw extending through said sole and projecting from the bottom surface thereof, a locking washer on said screw bearing against said bottom surface of the sole, said locking washer having a neck extending downward from the plane thereof and in binding engagement with said screw, said washer also having a circular series of ratchet teeth projecting down from the plane thereof, and a cleat in

threaded engagement with said screw with an end engaging said washer, said cleat having in said end a shallow recess the bottom and side surfaces of which are indented by said ratchet teeth.
